FIG. 1

FIG. 2

FIG. 3

FIG. 4

FIG. 5

Fig. 1 is a side elevational view of a combined knife and needle showing my new design as it appears in closed position;

Fig. 2 is an end elevational view as seen from the right of Fig. 1, the end opposite thereto being similar in appearance;

Fig. 3 is a side elevational view thereof as it appears with the end inverted to expose the knife and needle;

Fig. 4 is another side elevational view thereof as it appears rotated at an angle of 45°; and

Fig. 5 is an end elevational view as seen from the right of Fig. 4.

I claim:

The ornamental design for a combined knife and needle, substantially as shown and described.
